UNITED STATES PATENT OFFICE.

OTTO GEGRG, OF HERDECKE-RUHR, GERMANY.

FRictional SCREW PRESS.

Application filed June 9, 1927, Serial No. 197,611, and in Germany February 3, 1927.

This invention has reference to screw presses generally and it is intended to devise means of improving the manipulation and the manufacture thereof and to arrive at a more uniform and satisfactory mode of operation than it was possible to accomplish with the devices of this kind, as heretofore constructed. In view thereof my invention is chiefly concerned with novel means of driving and controlling the pressure producing means of such devices by the employment of friction discs and the like, and to generally improve the construction of such machines. Screw presses to be operated by means of friction discs have heretofore been generally constructed in such a manner that the vertically reciprocable operating spindle or shaft has been provided with a fly wheel which is turned to the left or right by the alternating frictional pressure producing engagement of two even side discs keyed to a common shaft. This arrangement has given very satisfactory results in the case of small friction presses, while in the case of larger sized presses this construction is open to various inconveniences, among which are to be mentioned very unsatisfactory utilization of energy, very heavy wearing of the tires, and most irregular rising of the center disc. This is due to the fact that, while upon the descent of the center disc or intermediate disc the acceleration thereof is proceeding from points of low velocity to points of high velocity, that is to say, in the most favorable mechanical ratio, conditions are entirely reversed upon the rising of said disc, inasmuch as in that movement the ascending disc is operated upon by the actuating disc for upward movement with high marginal velocity and since the said center or intermediate disc cannot readily follow on account of its large mass, considerable losses of energy are produced by sliding and grinding motion. Frequently conditions are so unfavorable that the intermediate disc cannot be made to ascend at all.

Various attempts have already been made to overcome these difficulties among which may be mentioned the expedient of arranging the side disc intended for the raising of the center or intermediate disc in such a manner as to be staggeringly disposed with relation to the disc for lowering the center disc, so that even in the ascent of the center disc the acceleration of said disc will take place from points of lower velocity to points of

higher velocity. In this case the regulation of the side discs is effected by the displacement of the upper shaft, while the staggeringly arranged side disc serving for the ascending movement is displaced by followers or the like in operative marginal engagement therewith. This manner of operation is very objectionable however, inasmuch as tilting and jamming of the lower shaft are unavoidable in this construction.

Now, my invention is designed to overcome these drawbacks of the previous construction by so arranging the shafts in the case of the staggeringly arranged side discs that each of the two shafts is centrally and separately operated, and in such a manner that both shafts are disposed to be simultaneously reciprocated.

The invention is shown by way of exemplification in two embodiments on the accompanying drawing in Figure 1, showing a press of the kind described in side elevation; Figure 2 is an elevation of one of the various modified constructions possible.

The center disc or intermediate disc or head 1 of the friction press is secured to the shaft or spindle 2 and is adapted to move up and down therewith and with the ram 3 connected to its lower end, the shaft being rotated to the left and right. Upon its descent the rotation of the center disc is caused for instance by the left-hand side disc 5 which is mounted on the same shaft 9 with the fast and loose pulleys, 6, 7 and with the right-hand small side disc 8. Upon its ascent the rotation of the center disc 1 is produced by the right-hand lower side disc 10 which may for instance be driven by a pair of gear wheels 11, 12 the upper one of which may be preferably made of raw-hide, and by means of the shaft 9. The operating discs are forced against the central disc 1 in such a manner that each of the said operating pressure discs is separately and individually moved by the pressure member or pressure slides 13, 14, adapted to be operated by two cinematically equivalent members, thus for instance by means of the elbow levers 15, 16 which levers are connected to each other by the link bar or pitman rod 17 in such a manner that the levers will perform exactly the same movement. By this means the steering and operation of the machine takes place without the liability of jamming and tilting, even with very heavy side discs. The movement of the link bar 17 is either effected manually by

means of the hand-lever 18, or by means of adjustable stops 19, 20 which are engageable by a contact 21 provided on the ram 3 and are adjustably mounted on a rod 18^a to which 5 the lever 18 is coupled, said rod being connected by the lever 17^a and link 17^b to the lever 16 and link 17. The operating or sliding elements 13, 14 are made to act centrally upon the discs 5, 10.

- 10 In Figure 2 a modification is shown which is of somewhat simpler construction, and in which the two equal two-armed levers 23, 23 which are suspended in the stationary fulcrums 24, 25 are connected to each other by 15 the common pivot 26 adapted to slide in longitudinal slots of the two levers. This pivoting stud 26 is operatively connected to a system of levers for the actuation of the two discs 5 and 10 in any suitable manner.
- 15 It will have to be understood that in practice modifications and changes in the construction and arrangement of the constituent parts are within the purview of my invention, except as otherwise stated and specified in 20 the appended claims.

I claim:—

1. In a frictional screw press the combination with an axially reciprocable screw spindle, a fly wheel secured to one end of the 30 spindle and a ram at the other end of the spindle, of operating friction discs, substantially at right angles to the intermediate fly wheel and engageable therewith and staggeringly disposed with relation to each other, 35 rotating means for one of said discs and operative connection of said means with the other friction disc, pressure producing means at the outside of said discs, substantially equal 40 operating levers for said pressure means, hingedly connected to each other, and operating means for said levers.
2. In a frictional screw press, the combination with an axially reciprocable screw spindle, and a fly wheel secured to one end 45 thereof, of operating friction discs arranged substantially at right angles to the intermediate fly wheel and staggeringly disposed in parallel spaced relation to each other, and engageable with said fly wheel, rotating 50 means for positively driving one of said friction discs, a raw-hide gear connected to the positively driven friction discs, an operative connection between said raw-hide gear and the other friction disc, a two-armed compressing lever for each of the two friction 55 discs, and means for simultaneously operating said levers.

3. In a frictional screw press the combination with an axially reciprocable screw spindle, a fly wheel secured to one end thereof and a ram secured to its other end, of operating frictional discs, substantially at right angles to the intermediate fly wheel and staggeringly arranged in parallel spaced relation to each other, rotating means for one of said discs, 60 an operative connection of said rotating means outside of the wheel engaging surfaces with the other frictional disc, a pair of substantially equal two-armed compressing levers for said discs outside thereof and operatively and slidingly engageable therewith, a link connection between the free ends of said pair of levers, an operative lever system to operate on said link connection, and means on the ram, operatively engageable with said 65 operative lever system.

4. In a frictional screw press, a movable head, a friction disk at one side of the head and movable into and out of driving engagement therewith, a plurality of friction disks at the opposite side of the head and arranged one above the other and movable together into and out of position for driving engagement with the head, a driving connection between the first-named disk and one of the second-named disks, a driving connection between the second-named disks, and means for simultaneously shifting the first-named disk and the second-named disks in opposite directions 70 relatively to the head.

5. In a frictional screw press, a movable head, a friction disk at one side of the head and movable into and out of engagement therewith, a pair of edgewise superposed friction disks at the opposite side of the head and movable together into and out of position for driving engagement therewith, a rotatable and slid able drive shaft carrying the first-named disk and one of said pair of disks, a second rotatable and slid able shaft carrying the other of said pair of disks, gearing between the shafts, and means for sliding said shafts in the same direction in unison.

6. In a frictional screw press, a movable head, a pair of disks disposed at opposite sides of the head and coupled to rotate in unison and slidably mounted for alternate engagement with and disengagement from the head, a third disk arranged edgewise in vertical alignment with and rotatable and slid able with one of the first-named disks, and means for shifting the disks.

In testimony whereof I affix my signature.
OTTO GEORG.
